CABLE SCORING TOOL FOR STRIPPING THE COVERING FROM A COAXIAL CABLE
J. Marves Mahoney, New York, N.Y.
(2269 Keller Lane, Salt Lake City, Utah 84169)
Filed Jan. 5, 1966, Ser. No. 518,810
4 Claims. (Cl. 30—90.1)

The present invention relates to a hand operated device adapted for use by various types of servicemen and manufacturers for removing the insulation and shielding on coaxial cables or the like in a selected series of steps. In cable work, it is important that the outer ends of the cables be stripped of insulation and shielding covering in a uniform fashion prior to making connection with other components but the stripping must be done without injury to the inner conductor and, usually, its adjacent insulating covering.

In the electronics industry, coaxial cables are used very widely. These are shielded wire cables. They possess many advantages over stranded-type cables having only fabric or insulating material as a covering. It is of great importance that the stripping of the jacket and shielding braid should be carried out with high precision and that the severed parts shall be properly and adequately selected in order that damage to the cable as a whole may not arise.

In the past, many types of devices have been proposed to achieve this result but, generally speaking, the prior art devices are difficult to use, they are expensive and, very frequently, require unusual type of clamping elements in order to use them. Further than this, many of the prior art devices include more than a single unit adapted for scoring or severing the insulation. These separate units operate without any adequate control and are difficult to maintain in relative adjustment so that the cutting or scoring may readily be restricted to that particular portion of the cable covering which it is desired to strip.

The device with which this invention is concerned comprises essentially a hand operated component which serves to strip the shielded cable wire, thereby to remove its outer jacket as well as the inner shield in a two-stage operation. The stripping unit usually comprises an outer barrel furnished with a wire collet and a center tubular section. With this, a cutting or scoring unit is provided to aid in locating the cable within the collet and also, when used with the positioned cable, to provide a means whereby through an oscillatory or rotary (or both) movement of the device relative to the cable, the cutting of the covering may be achieved. As the invention is constituted, it is free from all of the cam-type adjustments used in the prior art and, yet, the cable is securely and firmly gripped prior to severing the covering. Through the use of the adjustable collet, as a holder, the device is usable for different cable sizes. With the cutting instrumentality provided as a separate component adapted to be brought adjacent to the positioned cable, the depth of the scoring or cutting is readily controlled and limited.

With the foregoing thoughts borne in mind, a principal object of the invention is to provide an insulation stripping tool readily adapting itself to different size cables or wires and which is usable both for severing metallic braiding surrounding a central core and held adjacent to an insulating covering and in turn, covered by an insulating

2

covering so that separate cuttings of the different coverings may be achieved.

Another object of the invention is that of providing a cable stripper for removing insulation and shielding which will cleanly sever, and, in addition, to cut any desired length of insulation and shielding that can then be removed from the cable per se.

Further objects of the invention are those of providing a tool which is small enough to be hand carried and which is hand operated and for which there is no need or requirement of multiplicity of cutting or scoring edges.

Still other objects of the invention are those of providing a cable stripping tool in which there are no dies or blades to change for different size cables in the use of which it is impossible to damage the inner conductor insulation by reason of limiting the action relative to the shielding braid to that of scoring and not complete cutting, as well as to provide a tool structure which can be operated rapidly and efficiently and by which the shield braid may be severed by "work hardening" strands and then, breaking them by the use of the tool itself.

The invention has been illustrated in its preferred form by the accompanying drawings of which:

FIG. 1 is a showing of the tool in elevation;

FIG. 2 is a plan view of the structure of FIG. 1 particularly to illustrate the resilient or spring-like member used to position the cable relative to the collet and to provide the cutting edge;

FIG. 3 is an enlarged end view looking at FIG. 1 from the left for the purpose of showing the relative position of the resilient or spring-like guide member and the collet element;

FIG. 4 is a diagrammatic showing to represent the relationship between the coaxial cable and the blade holder and stop on the scoring member; and

FIG. 5 is an enlarged view showing the relationship established between the cable, the holding collet and the resilient member with the cutter or scorer.

Considering now the drawings for a further understanding of the invention, the tool comprises a relatively short handle member 11 (generally tubular as shown by FIGS. 1 and 2). The handle is adapted to be grasped by the operator, with the forward end 12 usually pointed away from the operator to receive a cable member (not shown). The coaxial cable, as above stated, comprises, essentially, an inner conductor about which is preferably wrapped a covering of insulation and over which there is a braided conducting member surrounding the complete inner conductor and its insulating covering. A second insulating covering forms an outer cover of the wire and surrounds the braided conductor. The foregoing structure is well recognized in the art as being the normal construction of coaxial cables.

The end of the tool opposite the handle comprises a collet 14 having a knurled or ridged gripping fingers of the cylindrical portion 15 adapted to be turned by hand to move the collet in and out along the hollow forward spindle end 16 of the tool. The collet contains the usual jaw or finger members, (see FIG. 5) which are brought together by tightening, and released by loosening, where the portion 15 is turned, as is well known. The inner end of the handle member 11 is formed into a collar portion 18, or the collar portion is secured to the handle in any desired manner. A flat spring-like element 20 is firmly

attached at one end 22 to the collar end 18 of the handle. The flat spring-like member extends generally parallel to the body of the tool from the fastening point on the handle to a region just slightly beyond the forward end of the collet 14. At the forward end, the spring member is bent inwardly, as shown at 24, until its inner end overlaps the collet opening. The inwardly turned end 24 of the spring member has a central aperture 26 which may be aligned with the collet opening by depressing the flat spring member 20 to bring it closely adjacent to the knurled or ribbed hand portion for turning the collet.

With the spring member so positioned and its aperture 26 substantially aligned with the opening in the collet, the shielded coaxial cable section may be inserted through the aperture 26 and the collet opening of the selected size. On the inwardly extending part 24 of the flat spring member 20 a notch 30 of generally V-shape is cut to assist in removing the insulation from the wire after appropriate scoring has been done.

In the use of the device, the tool is grasped by the handle portion 11 with the collet opening pointing outwardly. At this time, the flat spring 20 is depressed until the aperture 26 aligns itself and indexes with the collet opening. The cable to be stripped is then inserted through the aperture 26 and into the collet 14 with the collet then turned to adjust it to fit loosely around it. The flat spring 20 is then released and the tool is grasped about its handle end 11 only and rotated around the cable which is then held in the opposite hand of the worker from that in which the handle portion 11 is held so that the tool may be rotated through three or four revolutions. The cutting edge 32, which is exposed for a generally critical short distance, extends inwardly from the lower edge of the aperture 26 in such a manner that it may score the insulation about the cable. Normally, the cutting edge is formed as a sharp blade element and for the average size cable, the blade extends about 0.015 inch inwardly from the outer edge of the aperture.

With the scoring having been made by turning the tool about the cable positioned generally loosely in the collet 14, the next operational step is to tighten the collet collar 14 tightly upon the cable and then to rotate the tool through an angle of approximately 90° each way from the center axis so that three or four substantially half-turns are made. Following this, the collet 14 is loosened, the flat spring 20 is depressed and the cable is removed both from the tool and from passage through the aperture in the inwardly turned section 24 of the flat spring. With the removal of the cable from the tool, the cable is placed with the separating scar in the groove or notch 30 formed in the inwardly extending portion of the flat spring member. A strong pull on the cable, following location over the notch and maintenance of the position by the thumb of the user, will pull the cable away from the tool until the outer jacket and mesh shield are removed leaving the inner insulating covering completely intact.

The coaxial conductor is shown generally in section in FIG. 4 with the relationship of the cutting element or scoring blade depicted and the particular form of the cable for which this tool is designed is depicted by FIG. 4. FIG. 5 shows the relationship of the conductor, the supporting collet and the relationship of the resilient holder and cutter. The inner conductor 41 of most shielded wire is stranded to make it more flexible, although it need not necessarily be so. The inner conductor of either type is wrapped by the insulating covering 42 over which there is the shielding braid 43. External to the shielding braid, and forming the outside wrapping of the complete conductor, there is an outer insulating covering 44. In the cutting operation, the cutting blade 32 is supported at one end of the aperture in the downwardly turned section of the resilient member 20 where it is supported by a loop section 46 rolled over adjacent to the downwardly turned member. The blade holder thus formed stops the blade at the proper depth by scoring blade cuts through the

outer insulation and scores the shield braid as depicted.

The end of the resilient member, the collet and the securement of the resilient member 20 is particularly shown by FIG. 5. The structure, as described by reference to FIGS. 1 and 2 as related to FIG. 4 last discussed, is also generally depicted. The jaws 46 of the collet are adapted to close over the cable as the collet is turned upon the threaded end 48 are also clearly shown.

Various modifications of the foregoing structure are contemplated and may be made within reasonable skill in the art. Therefore, the invention is to be interpreted broadly except as limitations may be necessitated by reason of the claims to follow.

Having now described the invention, what is claimed is:

1. A device for stripping the ends of coaxial cables comprising, in combination,
  - an elongated body member having a handle at one end, a cable-receiving member having a generally centrally positioned cable-receiving opening located at substantially the opposite end,
  - a collet secured to the open end of the body member for tightening, with rotation, about a cable end adapted to be inserted therein,
  - a generally flat resilient member secured to the body member, between its ends, and extending substantially parallel and adjacent to the said body member in the direction of the open end thereof and the collet held thereby to overlap the open end of the collet, said resilient member having a downwardly extending end overlapping the cable-receiving opening in the collet,
  - said downwardly extending end having an opening therein through which the cable is adapted to be passed for insertion into the collet,
  - the downwardly extending end of said resilient member having an opening which when the said member is depressed against the body member is adapted to be substantially aligned with the opening in the collet so that with movement of the resilient member the cable may be inserted into the collet,
  - a cutting edge supported on at least one side of the opening in the downwardly turned resilient member, means to turn the device relative to the supported cable to score the cable covering, and
  - means to tighten the collet upon the body member following scoring firmly to secure a selected length of cable therein so that with further limited rotation of the resilient member about the gripped cable the cable covering may be scored for separation.
2. The device claimed in claim 1 wherein the downwardly depending resilient member is notched for receiving the scored outer covering of the cable whereby the covering may be removed with pull upon the located cable.
3. A device for stripping covering from a coaxial cable having inner and outer insulation separated by a braided metallic conductor comprising, in combination,
  - an elongated body member,
  - a flat spring member secured to the body member and extending generally parallel to the body member to overlap one of its ends said flat spring element having an inwardly turned lip at its end overlapping the body member and having an opening within the inwardly turned lip,
  - the opening being of a size sufficient to pass the end of a coaxial cable therethrough,
  - said body member having a substantially centrally positioned opening extending inwardly longitudinally thereof from the end adjacent to the inwardly turned lip of the flat spring member, a rotatable collet on the end of the body member adjacent to the inwardly turned lip of the flat spring member, said collet being adapted to be turned to tighten within it any cable length passed therein through the opening in the spring element,

said spring member being adapted to be depressed in the direction of the axis of the body member whereby the openings in the depending lip and the collet may be substantially aligned for the insertion there-through of a cable whose end covering is to be severed,

and a cutting element supported on the inwardly turned lip for scoring and cutting insulation on a gripped cable.

4. The device claimed in claim 3 wherein a cutting member on the inwardly extending lip is adjacent to the opening and on the side of the opening remote from the flat spring member whereby rotation of the flat spring

member relative to the body member relative to a cable positioned within the opening into the body member is adapted to score the cable covering for severing the same.
